LEONARD L. BLOCH, INVENTOR

BY

Charles H. Moran
ATTORNEY

Patented Oct. 23, 1928.

UNITED STATES PATENT OFFICE.

LEONARD L. BLOCH, OF NEW YORK, N. Y.

MEAT-SLICING MACHINE.

Application filed October 8, 1927. Serial No 224,789.

This invention relates to meat slicing machines, more particularly to that type of machine wherein the stock is mounted upon a reciprocating slide or table and is carried thereby in the path of a revolving knife or cutter.

One of the objects of the invention is to provide a new and improved means, whereby a hand operated slicing machine may be converted into a power driven machine at a minimum of cost, and whereby the converted machine will operate in substantially the same manner and with an efficiency equal to machines wherein the power driving mechanism is incorporated in the machine as originally produced.

Other objects and aims of the invention, more or less specific than those referred to above, will be in part obvious and in part 20 pointed out in the course of the following description of the elements, combinations, arrangements of parts and applications of principles, constituting the invention; and the scope of protection contemplated will be 25 indicated in the appended claims.

In the accompanying drawings, wherein I have illustrated a preferred form of embodiment of my invention,

Figure 1 is a side elevational view, showing 30 a slicing machine equipped with my invention;

Figure 2 is a side elevational view, partly in section, showing the manner of mounting the motor upon the slicing machine, and

Figure 3 is a similar view, showing the 35 manner in which the slicing machine is driven from the motor.

Referring now to the drawings, wherein similar reference characters refer to similar parts throughout the several views thereof, the reference numeral 1 denotes the base or standard upon which the slicing machine denoted generally at 2 is mounted, said slicing machine being provided with a rotary cutter 3 driven by a system of shafts and bevelled gearing indicated at 3, from the wheel 4. The wheel 4 which is a balance wheel, is mounted upon the shaft 5 shown in the dotted lines in Figure 1 of the drawings. The slicing machine which is illustrated by means of the pale lines in Figure 1 of the drawings, is of usual hand driven construction, in that it is mounted upon a reciprocating table and is carried intermittently into engagement 55 with the rotary cutting member 3, suitable

feed mechanism 5 being employed to feed the food product into position to be sliced by the constantly rotating cutting member 3.

The frame of the slicing machine is provided with a downwardly extending flange 7. Located on the inner side of said flange and suitably clamped thereto as by means of the bolts 8, is a plate 9, said plate being provided with a flanged or raised portion 10 which extends laterally, so that its front face 11 lies in the same plane with the outer surface of the flange 7. The flange 10 also engages with the lower edge of the flange 7. This construction, it will be noted, insures 70 a firm mounting for the driving mechanism.

The reference numeral 12 denotes the housing of the driving motor, said housing being provided with a T-shaped flange 13, the face of which lies in engagement with the outer surface of the flange 7, and the face of the flange 11 of the plate 9.

The clamp bolts 8 and 14 extend through the flange 13 of the motor, the flange 7 of the frame of the machine and the plate 9, 80 whereby all the said parts are clamped together and the motor supported rigidly in position upon the frame of the machine.

The driving wheel 4 of the machine is the usual hand or balance wheel, the handle of which has been removed. The balance wheel, 85 4 is provided with a peripheral groove or channel 15, which in the present instance, receives a link belt 16 which rides upon a pulley 17, is mounted upon a stud shaft 18 90 journaled in the housing 12 of the motor, said shaft being also provided with a gear wheel 19 driven by a pinion 20 fixed upon the drive shaft 21 of the armature of the motor.

An electric switch box 22 provided with a switch arm 23 is mounted upon the housing 12 of the motor.

It will accordingly be seen that I have provided a simple mechanism, whereby a hand operated slicing machine may be conveniently converted into an efficient power operated one at a modicum of cost, all that is necessary to be done, being to provide apertures in the flange 7 of the frame of the machine, 100 remove the operating handle from the drive or wheel 4, and groove the latter to convert it into a driven pulley wheel. The exposed operative parts are covered as by means of the housing 24 having the ears 25 bolted to 110 another housing 26 which forms a casing for the gear wheel 19 of the shaft 18.

The attachment is neat and attractive in appearance and is so located upon the machine as to be within the convenient reach of the operator thereof. Moreover the mounting of the motor is such that vibration is reduced to a minimum.

As many changes could be made in this construction without departing from the scope of the following claims, it is intended that all matter contained in the above description or shown in the accompanying drawings, shall be interpreted as illustrative only and not in a limiting sense.

Having thus described my invention, what I claim as new and desire to secure by Letters Patent, is:—

1. In a slicing machine, a frame having a downwardly projecting flange, a plate fitted to the rear surface of said flange, a motor housing having a flanged plate fitted to the front surface of said flange, means for clamping together said plate and the flange of the frame, a driving motor carried within said housing having a driving pulley, a grooved balance wheel for driving said slicing machine and a belt extended between said pulley and said balance wheel.

2. In a slicing machine, a frame having a downwardly projecting flange, a plate fitted

to the rear surface of said flange, said plate having a forwardly projecting flange which engages the lower surface of the flange of the frame, a motor housing having a flanged plate fitted to the front surface of said flange, means for clamping together said plate and the flange of the frame, a driving motor carried within said housing having a driving pulley, a grooved balance wheel for driving said slicing machine and a belt extending between said pulley and said balance wheel.

3. In a slicing machine, a frame having a downwardly projecting flange, a plate fitted to the rear surface of said flange, said plate having a forwardly projecting flange which engages the lower surface of the flange of the frame, a motor housing having a flanged plate fitted to the front surface of said flange, the plate of the motor housing also engaging the edge of the flange of said first plate, means for clamping together said plates and the flange of the frame, a driving motor carried within said housing having a driving pulley, a grooved balance wheel for driving said slicing machine, and a belt extended between said pulley and said balance wheel.

In witness whereof, I affix hereunto my signature.

LEONARD L. BLOCH.
